(57) **CLAIM**

We claim the ornamental design for a behind the head headset, as shown and described.

DESCRIPTION

FIG. 1 is a rear, left perspective view of the behind the head headset showing our new design;

FIG. 2 is front, right perspective view thereof;

FIG. 3 is a right side elevation view thereof, the left side elevation view being a mirror image thereof;

FIG. 4 is a bottom elevation view thereof,

FIG. 5 is a back elevation view thereof;

FIG. 6 is a top elevation view thereof; and,

FIG. 7 is a front elevation view thereof.

The broken lines showing a possible orientation with respect to a wearer and possible ear pads are for illustrative purpose only and form no part of the claimed design.
